ATOMIZER

Filed April 26, 1927

Fig. 1.

UNITED STATES PATENT OFFICE

CHARLES LIONEL MARCUS, OF NEW YORK, N. Y.

ATOMIZER

Application filed April 26, 1927. Serial No. 186,624.

This invention relates to spraying devices, such as atomizers adapted to be used for toilette, medicine, and the like purposes.

Among the objects of the invention is to provide an improved atomizer of the character described, which is particularly adapted to serve as a toilette accessory for dispensing liquid perfumes, which has novel means for collapsing a rubber bulb to provide an air supply for the spraying action, and which comprises few and simple parts, which, when assembled, form an ornamental toilette accessory, relatively inexpensive to manufacture, easy and simple to operate, and practical and efficient to a high degree in use.

Other objects of this invention will in part be obvious and in part hereinafter pointed out.

Certain features herein shown and described are shown, described, and claimed in my co-pending application Serial No. 178,249, filed March 25th, 1927, and accordingly are not claimed herein.

With the above exception, the invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational view, partially in section, showing the internal construction of a liquid perfume spraying device embodying the invention.

Fig. 2 is a cross-sectional view taken on line 2—2 in Fig. 1.

Fig. 3 is a fragmentary view showing a modified construction of the bulb collapsing means.

Referring in detail to the drawing, 10 denotes a spraying device, embodying the invention, and particularly adapted to dispense liquid perfumes. Said device is seen to comprise a container or bottle 11, made of

50 suitable material, preferably porcelain or

glass of any ornamental shape, for holding a supply of liquid perfume 12 to be sprayed from atomizing means mounted to form a closure for the top opening 11^a of the bottle. To secure the atomizing means in position, 55 a connecting collar 14 is fixedly mounted in the well understood manner, as by cementing to a shoulder portion 11^b on the rim of the container opening 11^a. This collar is internally threaded as at 14^a to engage with the 60 lower threaded portion 13^a of the casing 13 of said atomizing means.

The atomizer casing may be of any suitable cross-sectional shape and is here shown as being formed of a cylindrical tubing having a transversely extending partition wall 13^b formed with a downwardly concaved upper surface which serves as a seat 13^c for a rubber bulb 15. Said partition wall has a tubular portion 13^d extending axially downward therefrom into the bottle; and a nipple 16 formed with a peripheral lip 16^a is threaded into the seat so that the lip projects above the concavity over said tubular portion 13^d. 75

The bulb 15 has an opening 15^a to fit within the lip when assembled as shown in Fig. 1 and the seat is shaped to conform to the contour of the bulb, forming a rigid support therefor. If now the bulb is collapsed, air 80 will be forced therefrom into the bore 13^b of the tubular portion 13^d into the bottle. A regulator 17 is provided at the end of the tubular portion to control the flow of air into the bottle. Said regulator includes a 85

cap 18 having a wall portion 18^a which may be provided with suitable means for engaging the lower end of said tubular portion 13^d. A plurality of holes 18^b is provided in the wall portion 18^a adjacent the ends of said tubular portion, thus constituting adjustable means for throttling the holes 18^b, the degree of throttling varying as the regulator cap 18 is screwed up or down on the end of said tubular portion. The bore 13^b is enlarged 95 at the lower end, as shown at 13^c, to provide a chamber from which the supply of air may flow through the holes 18^b into the container 11.

The atomizing means also includes a nozzle 100

19 having an orifice member 19^a extending from the casing 13. Said member 19^a communicates with the container above the level of the liquid so as to freely receive air therefrom. For dispensing liquid from the container, an outlet tube 19^b is provided having its lower or intake end submerged in the liquid 12 and its upper or outlet end 19^c extending into the orifice member 19^a in coaxial relation therewith, leaving an annular passage 19^d for the air. The outlet tube 19^b may be secured to the casing by soldering, as at 20.

The bulb 15 is seen to occupy substantially the entire space within the casing 13 and is 15 provided with an air valve 22 to permit the bulb to fill with air in the usual manner. A suitable closure, such as top cover member 23, encloses the bulb in the casing. Said cover member may also serve as a base on which a 20 figure or other desired ornament 24 may be mounted.

For collapsing the bulb a push-button 25 is provided. Said button has one end extending through an opening 13^e, the other end 25 forming an extending projection or finger 25^a which concentrates the pressure exerted on the button to collapse the bulb easily. A flat spring 26 having its lower end suitably anchored in a recess 13^b formed in the casing 30 adjacent the partition wall 13^b, returns the button to its normal position.

The operation of the device 10 will now be clear. On applying pressure to the button 25, the finger-end thereof contacts with the 35 rubber bulb and collapses the latter against the opposite wall of the casing. The air from the bulb is forced through the tubular portion 13^a into the container where pressure will be exerted on the surface of the liquid 12 and cause the latter to rise and flow out of the 40 tube 19^b. Simultaneously, the air will flow through the orifice member 19^a to render a fine atomization of the liquid being sprayed from the outlet end of the tube 19^b.

If greater spraying effect is desired, the regulator cap 18 is adjusted to increase the size of the openings at the holes 18^b, thus providing a greater pressure for spraying the liquid 12 through the tube 19^b and causing 50 a correspondingly increased flow of air through the nozzle 19. When the device 10 is used as an accessory forming a part of a traveling outfit, or the like, the container may be filled with liquid and the regulator cap screwed up tightly to completely close the holes 18^b therein. If accidental pressure should be exerted on the push-button 25, the contents of the container will not be placed under air pressure from the bulb and 55 no liquid will be accidentally sprayed from the container nor will liquid spill should the device 10 be accidentally tipped over.

In Fig. 3 a modified construction of the bulb collapsing means is shown. Here a push 60 button 125 extends through an opening 113^e

in the casing 113, the inner end of the button being provided with an extending projection or finger 125^a which concentrates the pressure exerted on the push button to collapse the bulb 15 easily. The mid-portion of 70 the button is provided with a collar 125^b against which acts a coiled compression spring 127, said spring being wound about the mid-portion of the button. The collar and spring are enclosed in a housing 128 which is secured to the inside wall of the casing 113, the end wall 128^a of the housing 75 adjacent the finger 125^a serving as an abutment for the spring 127. The operation of the device 110 with the modified form of the bulb collapsing means is similar to that described above for device 10. On applying pressure to the button 125, the finger 125^a contacting with the rubber bulb 15 collapses the latter against the opposite wall of the casing 80 85 113 and the air is forced into the container for spraying the liquid in the container in the same manner as described for the device 10 above.

It will thus be seen that there is provided a 90 device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. In an atomizer of the character described, a resilient collapsible bulb to force air through the device for spraying a liquid therefrom, a tubular casing enclosing the bulb, said casing having an opening in the side thereof, a push-button extending through the opening, the inner end of the push button contacting with the bulb for concentrating pressure on the bulb to facilitate the collapsing thereof, and spring means for mounting said push button and retaining the same in its outwardly extended position.

2. In combination, a casing, air supply means mounted in said casing, actuating means for said supply means, and a spring support secured to said casing and to said actuating means for retaining said actuating means in operative position.

3. An atomizer comprising a container having an open upper end, a casing mounted on said end and having means therein for atomizing liquid from said container, said casing having a partition extending there-across and defining a compartment separated from said container, said atomizing means comprising a flexible bulb in said compartment communicating with said container and 120 125 130 135 140 145 retained on said partition, a nozzle secured in said partition and a wall of said casing for spraying and atomizing said liquid, and a pin for actuating said bulb extending through 5 said casing wall.

4. In a spraying device of the character described, a container, means for spraying a liquid from the container comprising a casing removably fitted on the container, a flexible bulb occupying substantially the entire 10 space within the casing, means projecting through the walls of the casing for collapsing the bulb in the casing, and a spring for carrying said collapsing means.

5. In an atomizer of the character described, a liquid container having a base on which it is adapted to stand, said container having an opening at its top, a tubular member having one end in registry with said opening, a releasable cover for the other end of 20 said member, a closure member in the end of said tubular member in registry with said opening in the container, and having an opening therethrough, a resilient bulb housed within said tubular member communicating 25 with the opening in said closure member, means for actuating said bulb for forcing air through said last named opening, a nozzle extending through said tubular member, and a liquid delivery tube communicating with 30 said nozzle.

6. In an atomizer of the character described, a liquid container having a base on which it is adapted to stand, said container having an opening at its top, a tubular member having one end in registry with said opening, a releasable cover for the other end of 35 said member, a closure member in the end of said tubular member in registry with said opening in the container, and having an opening therethrough, a resilient bulb housed within said tubular member communicating 40 with the opening in said closure member for forcing air therethrough, means extending laterally through said tubular member to 45 actuate said bulb, a nozzle extending through said tubular member, and a liquid delivery tube communicating with said nozzle.

In testimony whereof I affix my signature.
CHARLES LIONEL MARCUS.
